RAPID CENTRIC VERTICAL FINDER

Charles R. O'Donnell, Cleveland, Ohio

Application June 20, 1952, Serial No. 294,693

3 Claims. (Cl. 32—19)

This invention has relation to the centric and vertical and protrusive bite positioning of upper and lower jaw models on a dental articulator; reproducing on the latter these positions as they exist in the mouth.

It is the object of this invention to reproduce these positions without the necessity of the conventional wax bite rims. This eliminates the drawn out carvings requisite to building free gliding wax surfaces so bite rims may move laterally and occlusally in order that the scribing units (scribing screw and table) imbedded in them can function in unimpeded jaw excursions.

A further object of this invention is that its lower member in combination with its upper provides the dentist direct vision when its scribing pin is registering centric position on its scribing table. Its structure eliminates the use of an extraoral Gothic arch scribe now necessary for definite verification of this position, viz., that the scribing pin is on the apex of the scribed Gothic arch. As is known all present devices for scribing the Gothic arch require their mounting in wax bite rims, and when pin is on apex bite rims must be in occlusion, thus blocking off vision of centric position. This necessitates a device outside the mouth—an extraoral Gothic arch tracer—to verify definite centric position.

Another object of my invention is to provide a lower member secured to the lower base plate having an upright, such as a screw associated therewith, which may be adjusted to a position in which it will click against a member secured to the upper base plate when the base plates are positioned in the patient's jaws and the patient's lips are closed to a position in which he pronounces the letter M.

A further specific object of this invention is its guiding facility in providing a precise protrusive excursion in the median line for the protrusive bite. This differs from the protrusive bite of the prior art, taken with a heated mass of wax interposed between the bite rims and devoid of any guiding device, as will be hereinafter detailed.

A further object of this invention is that its structure provides the innovation of a detachable scribing table permitting the quick locking on of the table to its lower member with a single screw. This operation differs from that of the prior art in that it saves the time now necessary in fitting a scribing table into a wax bite rim.

Fig. 1 is a front elevational view of my improved structure, the base plates being shown in the patient's jaws and an adjustable upright being arranged between a member secured to the lower base plate and a member secured to the upper base plate with the upright being in the position it occupies when the patient's lips are closed to pronounce the letter M;

Fig. 2 is a side elevational view of the structure shown in Fig. 1;

Fig. 3 is a bottom plan view of the upper base plate and the member secured thereto taken on a plane passing through the dash-dot line of Fig. 2, looking in the direction of the arrows 3; and

Fig. 4 is a top plan view of the lower base plate and

2

the members secured thereto taken on a plane passing through the dash-dot line of Fig. 2, looking in the direction of the arrows 4.

Referring to the drawing, the numeral 7 is a horseshoe-shaped member which is secured to the base plate 14 which base plate is adapted to be seated in the lower jaw of a patient as shown in Figs. 1 and 2. The scribing table 8 is secured to the horseshoe-shaped member 7 by suitable means, such as a screw or bolt 1. Associated with the member 7 is an upright, such as a screw 6 having a knurled upper portion which screw is adjustably mounted in the horseshoe-shaped member 7 to such position that it will contact the upper member 15 the instant the patient's lips meet in pronouncing the letter M which establishes the vertical dimension as shown at 5 in Fig. 1. 2 shows scribing screw with a vertical range of space to roof vault 3. 10 is upper base plate seated in upper jaw.

Fig. 2 is a side elevation of Fig. 1 showing knurled screw contacting upper member at vertical dimension as shown by M contact of lips 4 and 4. Scribing screw 2 contacts its table and will maintain this correct vertical dimension at which the Gothic arch must be scribed—after knurled screw 6 is removed for the scribing.

In Fig. 3, 11 is upper member a crosspiece of metal or plastic attached directly to its base plate 10. If of plastic its expanded anterior will be of a metal surface to produce a metallic sound when knurled screw of lower member makes contact with upper in pronunciation. 30 This upper member is threaded at its center to carry vertical scribing screw 2. 12 is a median guide notch. The anterior of this member is expanded to permit marking by knurled screw of the requisite 6 millimeter protrusive bite shown as line 13. Anterior and posterior dots on 35 13 are guiding points in line with median notch explained later in operation of the device.

In Figs. 2 and 4 14 is the lower base plate. Sealed to it is horseshoe shaped lower member 7 with its anterior knurled screw 6. Locked to it by screw on right is scribing table 8. 2 is centric position at apex of Gothic arch tracing. Scribing table 8 is provided with a perforation or aperture to receive the knurled screw 6 associated with the horseshoe-shaped lower member 7.

Operation of the device.—In phase 1 of centro-vertical registration, the securing of jaw separation or the vertical dimension, the prior art uses the prosthetic concept that this separation is the one that exists the instant the wax bite rims contact when the patient says the letter M. Thus is required the construction of wax bite rims with the occlusal carving down or building of the latter to this dimension. The factor of vision makes this operation tentative rather than exact for at the instant of occlusal contact in pronouncing the guiding syllable M the lips must be closed. This inadequate vision forces the dentist to rely on his judgment in reference to the occlusal contact. To avoid this common visual handicap this invention uses sound instead of vision for this operation. While patient says letter M knurled screw is turned up until it clicks against upper member signalling

60 a precise vertical registration as shown by 5 in Fig. 1. It will be understood that scribing table 8 in this figure would be absent to permit pronouncing M. After this vertical registration is completed the knurled screw is turned down 3 millimeters to provide the conventional three millimeters free way space so plates will not click when talking. Without this conventional 3 millimeter space teeth would chatter, for in talking or in relaxation our lower jaw hangs down 3 millimeters.

Phase 2.—Referring to the prior art as it now secures the Gothic arch tracing to locate centric position, the occlusal wax surfaces spoken of in vertical dimension

in turn have to be carved into their lateral relations to permit the unimpeded lateral arc swing of the lower jaw. Free lateral gliding wax bite rim surfaces would be essential before the scribing members built into them could correctly trace the Gothic arch. This extended labor this invention eliminates since its structure provides a rapid nonimpeded and visible scribing of the Gothic arch. While knurled screw 6 in Fig. 2 maintains the vertical dimension, scribing screw 2 is moved down to table contact maintaining this dimension. Knurled screw is then removed to permit a visible nonimpeded Gothic arch scribing. Then patient bites on apex of, centric position, as upper and lower members are sealed together with plaster for transfer to dental articulator, reproducing on the latter centric and vertical relations as they exist in the mouth.

Phase 3 of centro-vertical relations, the protrusive bite.—In prosthesis this is expressed as "that progressively greater jaw opening that occurs posteriorly when lower teeth are protruded in a median line 6 millimeters forward into an incisal bite."

In the prior art this is secured by interposing a heated mass of wax between bite rims and having the patient bite forward 6 millimeters in a median line. The bite rims are then seated on their models which have already been placed in centric and vertical position on the articulator and they are closed into this protrusive bite wax imprint. This seating of the models into imprint swings the condylar pitch indicators of the articulator into whatever jaw opening the wax mass imprint offers. With patients who are awkward in jaw movement it is often difficult to get the patient to bite a median 6 millimeter protrusive excursion into a wax mass since this is an unguided operation.

The structure of this invention provides a guided median and anterior 6 millimeter protrusive excursion to register the purpose of this excursion—the posterior jaw opening. Both members are placed on the articulator and it is closed in centric position permitting a centric mark where knurled screw makes contact on upper members as shown by posterior dot on line 13 in Fig. 3. A line is then measured forward 6 millimeters in alignment with median notch 12 of upper member. Knurled nut contacts the terminal of this line 13 as represented by its anterior dot and this point is marked. The patient biting on this anterior protrusive bite guiding mark would be creating the correct posterior jaw opening sought for in the operation of the protrusive bite. This operation is more easily visualized in side elevation Fig. 2. It may be seen that if the patient bites the knurled screw out 6 millimeters against upper member the table 8 would move away from the scribing screw point registering the progressively greater posterior jaw opening space. If while the patient bit on the 6 millimeter median anterior protrusive guide bite marked on upper member and the dentist turned the scribing screw

down into table contact the lengthened screw would exactly register this posterior bite opening for the articulator. Placing the member on the articulator and closing it as was done on the wax bite imprint its condylar indicators would swing to the pitch or posterior jaw opening registered by the lengthened scribing screw thus providing the precise requisite of the protrusive bite.

Having described the invention what is claimed as new is:

1. The combination of upper and lower base plates, an upper member secured to the upper base plate, a horseshoe-shaped member secured to the lower base plate, a screw mounted in the horseshoe-shaped member, a scribe table arranged over the horseshoe-shaped member and having an aperture through which said screw extends, means for securing the scribe table to the horseshoe-shaped member, and said screw being adjustable to a position in which it engages the upper member when the plates are in the jaws of a patient's mouth and the patient's lips are closed to a position in which he pronounces the letter M.

2. The combination of upper and lower base plates, an upper member secured to the upper base plate, a horseshoe-shaped member secured to the lower base plate, a screw mounted in the horseshoe-shaped member, a scribe table arranged over the horseshoe-shaped plate and having an aperture through which said screw extends, said screw being adjustable to a position in which it engages the upper member when the plates are in the jaws of a patient and the patient's lips are closed to a position in which he pronounces the letter M, and a scribing screw mounted in the upper member and being adjustable to a position in which it engages the scribe table when the lower jaw of the patient is moved outwardly to a protrusive-bite position.

3. The combination of upper and lower base plates, an upper member secured to the upper base plate, a lower member secured to the lower base plate, a screw mounted in the lower member, a scribe table arranged over the lower member and having an aperture through which said screw extends, said screw being adjustable to a position in which it engages the upper member when the plates are in the jaws of a patient and the patient's lips are closed to a position in which he pronounces the letter M, and a scribing screw mounted in the upper member and being adjustable to a position in which it engages the scribe table when the lower jaw of the patient is moved outwardly to a protrusive bite position.
